DOORSTOP

Bernard E. Fisher, Detroit, Mich.

Application June 12, 1946, Serial No. 676,149

5 Claims. (Cl. 16—86)

1

This invention relates generally to bumpers and more particularly to door stops.

In the past the type of door stop used in homes and other buildings usually consisted of a metallic extension member or rod having a wood screw thread formed on one end thereof to secure the stop to a wooden baseboard or in some cases to the door, the other end of the rod usually being covered by a rubber bumper tip. This type of door stop performed its intended function successfully, namely preventing the door from hitting the baseboard or wall, but is objectionable in other respects. For example, these rigid door stops are quite frequently struck or hit sideways by passing objects or people with the result that the threaded end of the stop becomes loosened in the baseboard or in the door. Consequently, from time to time it becomes necessary to refill these enlarged screw holes or to screw the stop into the baseboard or door in a new location, which is of course objectionable.

Accordingly, it is an object of the present invention to provide a new and improved door stop in which the above mentioned objections are obviated.

More specifically, it is an object of the present invention to provide a laterally movable or flexible door stop which will flex if struck sideways without transmission of the force to the door and/or to the baseboard on which the stop may be mounted.

Another object of the invention is to provide a laterally movable stop which will always return to its normal position.

Another object of the invention resides in the novel arrangement and connection between the parts to insure centering of the stop member, to support the stop member and to hold a cap over the outer end of the holding screw.

A further object of the invention is to provide a stop of the above mentioned character which will be inexpensive to manufacture.

A still further object of the invention is to provide a laterally swingable door stop which may be held by tensioned, slip-on attaching means to a door.

Other objects of the invention will become apparent from the following detailed description taken in connection with the accompanying drawing in which:

Figure 1 is a sectional view taken longitudinally of a door stop member embodying features of the present invention.

Figure 2 is a view in elevation of the door stop, taken along the line 2—2 of Figure 1.

2

Figure 3 is a sectional view taken longitudinally of a modified form of my door stop.

Figure 4 is a view in elevation of the door stop taken along the line 4—4 of Figure 3 and

5 Figure 5 is a fragmentary elevational view of the door stop of Figure 3 looking in the direction of the arrows 5—5 of Figure 3.

Referring to the drawing and first to Figures 1 and 2, the door stop shown may be secured to a mounting 10 which may be a door or may be the baseboard of a room, as desired. The door stop comprises in general, a supporting member or screw 11 and a door stop member 12. The door stop member 12 is carried or is supported by the screw 11, extending therefrom for abutment with the door or baseboard, as the case may be. The screw 11 comprises a threaded portion 13, a second threaded portion 14 and an intermediate head 15. The threaded screw portions 13, 14 are integral with the intermediate head 15 extending respectively from opposite sides thereof. As shown in the drawing, the threaded portion 13 may have a wood screw thread and be screwed into the wooden mounting 10 until the head 15 abuts thereagainst.

30 The stop member 12 is an elongated, laterally movable or flexible member which will yield sideways without transmitting the force of such movement to its supporting screw 11. To this end, I prefer to use a helical coil of wire in the form of a coil spring and to use a coil having abutting convolutions to provide a so called solid member longitudinally thereof. One end of the coil or stop member 12 is tapered, as at 16, and threads onto the threaded screw portion 14, thus attaching the coiled stop member 12 to its support or screw 11. Preferably, a bumper tip 17 is provided and fits over the other end of the coiled stop member 12, the tip 17 being made of a suitable resilient material, such as rubber.

35 A bell like cap 18 fits over and surrounds the screw head 15, threaded screw portion 14 and an end portion of the coiled stop member 12, the large end of the cap seating against the side of the door or baseboard 10, as the case may be. At the other or outer end of the cap 18 there is an opening 20 where the metal is reversely bent inwardly providing a conical seat 21 converging or tapering inwardly of the cap 18. The tapered end 40 portion 16 of the coiled stop member 12 seats and wedges tightly in and against the conical seat 21 when the coiled stop member 12 is threaded onto the screw portion 14 and tightened down. This 45 conical seat 21 for the coiled stop member 12 acts 50 to center it or to normally hold the member 12 55 to center it or to normally hold the member 12

such that its longitudinal axis will be at right angles to the surface against which the bumper is to hit. In other words, the conical seat 21 corrects the tendency of the coiled stop member 12 to extend at an angle normal to the pitch angle of the threaded portion 14. It will also be seen that threading of the tapered end of the coiled stop member 12 onto the threaded screw portion 14 against the conical seat 21 serves as the sole means for holding the cap 18 in place against the mounting 10 thus, eliminating need for screws or other fastening means holding the cap in place.

In the modification of Figures 3, 4 and 5, there is a door 22 on which the coiled door stop member 12 is mounted by means of a supporting member 23. This supporting member 23 is preferably made of a strip of spring sheet metal bent in a general U-shape having a leg 24, a leg or spring clip portion 25 and a joining base portion 26. As shown, the supporting member 23 slips on the bottom of the door with the base 26 against the lower door edge, the leg 24 flat against one side of the door and the leg 25 flat against the other side thereof. The supporting member 23 is frictionally held to the door by the tensile force exerted by the clip portion or leg 25.

Formed out of the leg 24, a supporting boss 27 for the stop member 12, preferably of conical form has an opening 28 in its outer end where the metal is reversely bent inwardly of the cap, providing a conical seat 29 for the tapered end of the stop member 12. At its inner edge, the conical seat 29 is provided with an inturned, continuous flange 30 for attaching the tapered end of the stop member 12 to its support 23. As shown in the drawing, the tapered end of the coil or stop member 12 is attached to the outer end of the supporting boss by placing the terminal end of the coil through the opening 28 behind the flange 30 and then turning the stop member 12 until one or more of its coils lodge behind the flange 30 in the boss 23. In this way the stop member or coil 12 is held and supported by the supporting member 23 without need of separate or additional attaching means.

From the above description it will be appreciated that in either form of the invention, the stop member by reason of being laterally yieldable will not transmit a laterally directed force thereagainst to its support with the result that the stop member supports will not be loosened. In the form of door stop of Figure 1, the conical seat of the cap serves to center the coil stop member which in turn forced against the conical seat serves as the sole means to hold the cap in place. This eliminates need for screws or other fasteners to hold the cap in place thus reducing cost of the door stop. The form shown in Figure 3 is a simplified form in which the supporting screw is replaced by a tensioned supporting member which slips on the bottom of a door. This stop member, in addition to being flexible so as not to transmit laterally directed forces thereagainst to the stop member support, is attached directly to its support without need of separate attaching means.

It will be understood that various forms of the invention other than those described above may be used without departing from the spirit or scope of the invention. Accordingly, the invention is to be limited only as indicated by the scope of the appended claims.

Having thus described the various features of my invention, what I claim as new and desire to secure by Letters Patent is:

- 10 1. A door stop comprising, a supporting member having a threaded portion, a cap member over the threaded portion of said supporting member, said cap having a conical opening converging inwardly thereof surrounding the threaded portion of said supporting member, a coil spring having an outer bumper end, said coil spring having an inner tapered end portion seating in the conical seat of said cap member and threadedly connected to the threaded portion of said supporting member.
- 15 2. A door stop for supporting on a mounting comprising, a support having a threaded portion to screw into the mounting and having a second threaded portion to extend from the mounting, a cap member over the second threaded portion to seat against the mounting, said cap having a conical opening substantially co-axial with the second threaded portion and tapering inwardly of the cap, a coil spring having a tapered end portion seating in the conical opening of said cap and threaded onto the second threaded portion for solely holding the cap to the mounting and for centering the spring, and a bumper tip on the outer end of the coil spring.
- 20 3. A door stop comprising, a supporting member for attachment to a wall, a socket member surrounding said supporting member and adapted to engage the wall, and a helical coil stop member attached to said supporting member in said socket member and urging the latter against the wall.
- 25 4. A door stop comprising, a supporting member having an outer threaded shank portion, a cap member surrounding said threaded shank portion having an outwardly facing conical socket and a laterally flexible coiled bumper member having a conical end threaded onto said shank portion in said conical socket.
- 30 5. A door stop comprising, a securing member having an outer threaded end portion, a cap member to surround the outer threaded end portion of said securing member having a conical socket, and a helical coil bumper member having a tapered end for threading onto the threaded end portion of said nail and for engaging in said socket to hold said cap in place.
